UNITED STATES PATENT OFFICE

2,490,820

SEALING MEANS FOR LIFTER ROOF TANKS

Donald E. Larson, Eureka, Calif., assignor to Chicago Bridge & Iron Company, a corporation of Illinois

Application July 11, 1946, Serial No. 682,872

9 Claims. (Cl. 48—176)

1

This invention relates to a lifter roof tank for the storage of gas or mixtures of liquid and gas, and relates particularly to an improved sealing means for such tanks.

In the ordinary construction of lifter roof tanks for the storage of gas or mixtures of liquid and gas, it is common practice to provide a shell with a lifter roof thereover adapted to rise and fall with increasing and decreasing gas pressure within the tank. In order to seal the area between the shell and the roof, flexible sealing means is used, such as a fabric impregnated with a flexible impervious solid. Ordinarily synthetic rubber is used for this purpose. This construction puts a great strain on the flexible sealing member, as it must withstand all the pressure of the confined gas within the tank. Various means have been proposed in the past for backing up or reinforcing the flexible sealing member, but these have not all been entirely satisfactory.

The present invention provides a sealing means including a flexible sealing member that is supported by spaced hinged members around the tank extending from the shell to the floating roof. These hinged members are hingedly connected together in pairs with one member of each pair hingedly connected to the roof and the other member hingedly connected to the shell. As the roof rises and falls the members turn around their hinges so as to accommodate themselves to all positions of the roof. The invention broadly comprises spaced pairs of supporting arms with the arms of each pair hingedly attached together at their ends with one arm having its other end attached to the roof and the second arm having its other end attached to the shell, each of said pairs of arms extending inwardly when the roof is in its highest position, and the roof end of the roof arm extending beyond the shell and the hinged connection of the two arms extending beyond the shell when the roof is in its lowest position. There is provided a flexible sealing member extending between the shell and the roof and supported by the supporting arms on the inner sides thereof.

The invention will be described as related to the embodiment shown in the accompanying drawings. Of the drawings Fig. 1 is a fragmentary vertical section through the top edge of the lifter roof tank of this invention showing the roof in its lowest position; Fig. 2 is a view similar to Fig. 1 but with the roof in its highest position; Fig. 3 is a horizontal section taken along line 3—3 of Fig. 2; and Fig. 4 is a section taken along line 4—4 of Fig. 2.

2

The lifter roof tank comprises a shell 10, a lifter roof 11 thereover, a depending skirt 12 around the edge of the roof and beyond shell 10, spaced brackets 13 at the top of the shell 10 extending inwardly and inclined upwardly, radial support members 14 within the shell and fastened to the ends of the brackets 13 for supporting the roof 11 when the roof is in its lowest position, and an inverted channel member 15 at the bottom of the roof skirt 12. The spaced brackets 13 support an inclined plate 16 extending inwardly from the shell 10. A flexible sealing member 17 of fabric impregnated with a flexible impervious material such as synthetic rubber extends between the channel 15 on the roof and the inclined plate 16 on the shell. The shell end of this flexible member is held by means of a washer bar 18, while the roof end of the flexible member 17 is held in sealing relationship against the inner flange of the channel 15.

In order to support the flexible member 17 spaced pairs of plates 19 are provided around the tank. These plates are of rectangular shape and have a longitudinal edge of each hingedly attached together, while the other longitudinal edge of one plate is hingedly attached to the roof and the other longitudinal edge of the second plate is hingedly attached to the shell. The hinge constructions are shown in Fig. 4. The outer plate 20 is of greater width than the inner plate 21. The outer plate 20 is hingedly attached to the inner flange of the channel 15 by means of hinge brackets 22 mounted on the channel with each hinge bracket holding a pin 23 extending into a circular edge 24 on the outer plate 20. The inner plate 21 is hingedly attached to the inclined plate 16 by means of similar hinge brackets 25, pins 26, and circular edge 27. The two plates 20 and 21 are hinged together by means of a long hinge pin 28, and interfitted circular edge portions 29 and 30.

As can be seen in Figs. 1 and 2, the outer edge of the outer plate 20 of each pair extends beyond the shell 10. Likewise the hinged connection between the two plates of each pair extend beyond the shell when the roof is in its lowest position. When the roof is in its highest position both plates of each pair extend inwardly. The pairs of plates have their hinged sides extending in straight lines and the plates are arranged around the tank like chords on a circle. As the roof rises and falls the hinged plates readily accommodate themselves to all positions of the roof and serve to back up the flexible sealing member 17 at all times.

55 Any of the usual guide and stabilizing means

may be provided on the tank, and the usual vents, safety valves, and the like may also be provided.

As the outer ends of the outer plates 20 and the inner ends of the inner plates 21 are hingedly supported on the roof and the shell at only two points for each edge the channel 15 may be of circular shape and the shell plate 16 may be shaped like the frustum of a cone. It is of course necessary that the hinge brackets 22 of each outer plate 20 be arranged in a substantially straight line and that the hinge brackets 25 of the inner plates 21 also be arranged in a straight line. It is also necessary that the connected edges of each pair of plates be in a straight line and that all plates be of substantially rectangular shape.

Having described my invention as related to the embodiment shown in the accompanying drawings, it is my intention that the invention be not limited by any of the details of description unless otherwise specified, but rather be construed within its spirit and scope as set out in the accompanying claims.

I claim:

1. In a lifter roof tank comprising a shell and a lifter roof thereover with the roof having a depending skirt, sealing means comprising horizontally spaced pairs of supporting arms with the arms of each pair hingedly attached together at their ends with one arm having its other end hingedly attached to the skirt and the second arm having its other end hingedly attached to the shell, said pairs of arms forming a collapsible V-shaped structure which opens outwardly when the roof is in its highest position and the skirt end of the skirt arm extends beyond the shell and the hinged connection of the two arms extends beyond the shell when the roof is in its lowest position and a flexible sealing member extending between the shell and the roof and supported by said supporting arms on the inner sides thereof.

2. The sealing means of claim 1 wherein at least one of said arms is a substantially straight flat plate.

3. The sealing means of claim 1 wherein each arm is a substantially straight flat plate.

4. The sealing means of claim 1 wherein the top of the tank shell is provided with a support including a surface inclined inwardly and upwardly and the shell edges of the plates are hingedly mounted on said surface.

5. In a lifter roof tank comprising a shell and a lifter roof thereover with the roof having a depending skirt, sealing means comprising spaced pairs of flat substantially rectangular plates around the tank with the plates of each pair being hingedly attached together at longitudinal edges and with the other longitudinal edge of one plate being hingedly attached to the skirt and the other longitudinal edge of the second plate being hingedly attached to the shell, said plates forming a collapsible V-shaped structure which opens outwardly when the roof is in its

highest position and a continuous annular sealing member extending between the shell and the skirt and supported by said pairs of hinged plates on the inner surfaces thereof.

6. The sealing means of claim 5 wherein the top of the tank shell is provided with a support including a surface inclined inwardly and upwardly and the shell edges of the plates are hingedly mounted on said surface.

7. The sealing means of claim 5 wherein all hinged connections are in straight lines and the pairs of plates are arranged around the tank substantially like chords to a circle.

8. The sealing means of claim 5 wherein all hinged connections are in straight lines, the plates are substantially equal in length, and the pairs of plates are arranged around the tank substantially like equal chords to a circle.

9. In a lifter roof tank comprising a shell, a lifter roof thereover, and a depending skirt at the edge of the roof beyond the shell, sealing means comprising a support at the top of the shell including a surface inclined inwardly and upwardly, spaced pairs of flat substantially rectangular plates around the tank with the plates of each pair being hingedly attached together at longitudinal edges and with the other longitudinal edge of one plate being hingedly attached to the skirt and the other longitudinal edge of the second plate being hingedly attached to the inclined surface, said plates forming a collapsible V-shaped structure which opens outwardly when the roof is in its highest position and the hinged connection of each pair of plates extending beyond the shell with the skirt plate being parallel to the skirt and beneath the other plate when the roof is in its lowest position, and a flexible sealing member extending between the shell and the roof and supported by said pairs of hinged plates on the inner surface thereof, said roof plates being connected to the skirt along straight lines, said shell plates being connected to the inclined surface along straight lines and said hinged connections between plates of each pair being in straight lines and the pairs of plates being arranged around the tank substantially like equal chords of a circle with all said plates being substantially equal in length.
